LAMP

James C. Downey, Aiken, S.C.

Application April 7, 1958, Serial No. 50,369

Term of patent 14 years

(Cl. D48—20)

The sides of the lamp not shown are substantially the same in appearance as the sides shown and the base is circular and plain.

The top shade member is shaded to show contrast.

The dominant features of my design reside in the portions shown in full lines.

I claim:

The ornamental design for a lamp, as shown and described.
